UNITED STATES PATENT OFFICE.

WILLIAM T. SMITH, OF PHILADELPHIA, PENNSYLVANIA.

DESIGN FOR FRINGE.

SPECIFICATION forming part of Design No. 35,814, dated March 11, 1902.

Application filed February 17, 1902. Serial No. 94,570. Term of patent 14 years.

To all whom it may concern:

Be it known that I, WILLIAM T. SMITH, a citizen of the United States, residing in Philadelphia, Pennsylvania, have invented and produced a new and original Design for Fringe, of which the following is a specification.

My design is fully shown in the accompanying drawing.

The design comprises a fringe composed of loops projecting inwardly beyond the edge of the fabric and terminating in knots adjacent to said edge, these knots being arranged in groups, from each of which groups depends a plait terminating in a tassel.

In the drawing, 1 represents a portion of the fabric to which the fringe is applied; 2, the loops projecting inwardly beyond the edge

of the fabric; 3, the knots adjacent to said edge; 4, the plates depending from groups of such knots, and 5 the tassels at the lower ends of said plaits.

Having thus described my invention, I claim and desire to secure by Letters Patent—

The design for a fringe for fabrics, substantially as described and as shown in the accompanying drawing.

In testimony whereof I have signed my name to this specification in the presence of two subscribing witnesses.

WILLIAM T. SMITH.
